(57) **CLAIM**

The ornamental design for a traffic cone, as shown and described.

DESCRIPTION

FIG. 1 is a perspective view of a traffic cone showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged perspective view thereof; and,

FIG. 9 is an enlarged front view thereof.

The broken lines illustrate portions of the traffic cone that form no part of the claimed design.
